SLIDE PROJECTOR

Hans Mulch and Heinrich Janke, Wetzlar (Lahn), Germany, assignors to Ernst Leitz G.m.b.H., Wetzlar, Germany

Filed Oct. 29, 1962, Ser. No. 72,289

Term of patent 14 years

(Cl. D61—1)

Fig. 1

Fig. 2

Fig. 3

FIGURE 1 is a front elevational view of a slide projector showing our new design;

FIGURE 2 is a side elevational view thereof; and

FIGURE 3 is an overall perspective view thereof.

The rear of the projector, not shown, is substantially plain except for conventional switch and cord connections.

We claim:

The ornamental design for a slide projector, as shown and described.
